INTERNAL-COMBUSTION ENGINE.

1,129,100.

Specification of Letters Patent. Patented Feb. 23, 1915.

Application filed February 13, 1911. Serial No. 608,399.

To all whom it may concern:

Be it known that we, EDWARD A. JOHNSTON and CHARLES I. LONGENECKER, citizens of the United States, residing at Chicago, in the county of Cook and State of Illinois, have invented certain new and useful Improvements in Internal-Combustion Engines, of which the following is a specification.

10 Our invention is applicable to all internal combustion engines, and in particular to those wherein an explosive mixture of liquid fuel and air is used, and in its specific organization is designed for use in engines 15 using any of the heavier liquid fuels, such as crude petroleum or kerosene or alcohol. We have discovered that the reliability of the engine operation and its efficiency in converting into work the heat of combustion of 20 such heavy liquid fuels is largely dependent upon a proper control of the temperature of the walls of the cylinder and combustion chamber among other things. We have found that it is necessary to maintain substantially a constant temperature in all the 25 walls in contact with the explosive mixture, and, furthermore, that it is desirable and possible to secure an automatic control of this temperature in spite of natural tendencies for it to vary with the quantity of 30 mixture exploded in accord with the load demands.

The object of our invention is to provide an organization of mechanical elements that 35 will attain such results in a practical and satisfactory manner. We attain this object by means of the mechanism illustrated in the accompanying drawings, in conjunction with an engine utilizing heavy oils after being warmed by a preliminary use of gasoline or other easily vaporized liquid fuel, but the mechanism of our invention may take other forms or be used in conjunction with other devices and arrangements than those illustrated by these drawings, in which—

Figure 1 is a side elevation of an internal combustion engine having our invention forming a part thereof; Fig. 2 is an end elevation of Fig. 1; Fig. 3 is a sectional elevation of a condenser forming part of the cooling water circulating mechanism; Fig. 4 represents a sectional elevation of a constant level cup communicating with the water chamber surrounding the engine cylinder and with a source of supply of cooling

water; Fig. 5 represents a detached detail of part of a water circulating pump.

The same reference characters designate like parts throughout the several views.

1 represents a base frame, upon which is secured the engine frame 2, and 3 represents the engine crank shaft, 4 the cylinder secured to the opposite end of the frame, the cylinder being provided with a surrounding annular chamber 5 for the reception of a circulating cooling medium, as water, the source of supply of the water being a tank 6 carried by the base frame 1.

7 represents an inlet valve communicating with the combustion chamber, and includes 70 a vertically arranged stem 8 slidably mounted in a bearing member integral with a curved mixture feed conduit 10, having a flange 11, whereby it is secured to the outer wall of the cylinder. The upper end of the 75 valve stem is encircled by a compression spring 13 that is operative between the wall of the conduit and a pressure regulating nut 14 in a well-known manner to control the movement of the valve. The conduit curves 80 upward and outward toward the head of the cylinder and is provided with a flange 15 at its outer end whereby it is secured to a corresponding flange 16 at the lower end of a hollow carbureter member 17 that curves 85 outward and vertically and having its upper end communicating with the atmosphere. Surrounding the vertical portion of the carbureter is a casing 18, having a series of annular chambers therein, one of which is connected with the source of water supply by means of a pipe 20, and having an overflow pipe 21 projecting into its interior whereby a constant level of water is maintained in the chamber, and 22 represents a common 90 form of needle valve that controls the admission of water into the interior of the carbureter. Other of said chambers 23 are respectively connected with sources of heavy liquid fuel supply and gasoline or other 95 easily vaporized liquid fuel supply.

33 represents a common form of butterfly valve mounted upon a stem 34 that is adapted to rock in bearings formed in the wall of the carbureter above the annular chamber 105 and operative to control the admission of air to the carbureter. A similar throttling valve is pivotally mounted within the carbureter intermediate the needle valve mechanism and the intake valve, and operative to 110

control the admission of mixture to the combustion chamber. The charge throttling valve is mounted upon a stem similar to that of the air controlling valve, and 36 represents a double armed lever secured to the stem, and one arm of the lever is designed to be connected with the governor mechanism of the engine, as by a rod 37, the opposite end of the lever being connected by 10 means of an adjustable link 38 on the lever arm 39 secured to the stem 34 of the air controlling valve, whereby the two valves are operated in unison by the governor mechanism to control the volume and proportion 15 of mixture admitted to the combustion chamber.

38¹ represents an exhaust valve mechanism that may be connected with an operative part of the engine by means of a lever 20 39¹ and 37¹ represents an exhaust pipe leading upward from the lower part of the combustion chamber.

40 represents a constant level water supply cup secured to the side of the cylinder, 25 having its lower end communicating with the annular water receiving chamber surrounding the cylinder by means of a port 41 having a check valve 42 located therein that opens toward the chamber. The cup receives its water supply through its connection with the overflow pipe 21 of the water chamber in casing 18 of the carbureter mechanism, and 43 represents an overflow pipe projecting into the interior of the cup 40 30 leading to the bottom of tank 6, the check valve 44 closing against the tank.

45 represents a water circulating pump mounted upon a bracket 46 secured to the engine frame and having the plunger 47 35 operatively connected by means of a pitman 48 with an eccentric 49 secured to the engine shaft, and a valve chamber 50 by means of an inflow pipe 51 with the water supply in the tank 6, and an outflow pipe 52 leading 40 in a vertical direction to deliver the water into the upper end of a condenser 53, the lower end of the condenser communicating with a spray pipe 54 arranged across the upper end of tank 6.

55 represents a feed pipe connected with the outflow pipe from the pump below the condenser and leading to pipe 20 connected with the water chamber of the carbureter mechanism, and 56 an outlet pipe leading 50 from the upper part and near the center of the length of the water chamber surrounding the cylinder to the condenser.

The level of the water in the feed cup that supplies cooling water to the chamber 60 surrounding the cylinder is approximately in the same horizontal plane with the upper part of the chamber.

To start the engine, when the cylinder and combustion chamber are at a low temperature insufficient to properly vaporize the

heavier liquid fuels, gasoline or other easily volatilized liquid fuel is admitted from the source of supply, and as soon as the combustion chamber becomes heated the gasoline supply ceases and kerosene is admitted. In 70 this type of engine the most of the heat of combustion of the explosive mixture that is given to the inclosing walls is received by those bounding the space between the cylinder head and inner position of the piston 75 commonly called the combustion chamber and during the ignition of the charge. After the explosion the temperature of the gases rapidly and continuously falls as the piston makes its power stroke, and consequently the walls of that portion of the cylinder uncovered by this outward piston movement are but slightly heated, while the walls of the combustion chamber may be highly heated. This unequal wall heating 80 results in an uneven distribution thereof throughout the cooling water in the surrounding jacket, that portion surrounding the combustion chamber being heated to boiling before other parts nearer to the open 85 end of the cylinder become fairly warm. The steam thus formed near the cylinder head will form a pocket and build up enough steam pressure to force the water toward the outlet pipe, up it and across the horizontal pipe into the condenser and thence to the supply tank, this discharge of water by steam pressure being followed by steam itself until the pressure is relieved. The outflow 90 of water from the jacket and its relief of pressure is followed by an inflow of colder 95 water into it from the constant level cup, which momentarily cools the jacket but shortly after the whole operation automatically repeats itself. The intermittency of the flow of water in and out and steam out being determined by the heat generated by the burning gases, and the volume of the latter in turn by the load upon the engine, the steam and water in varying recurring 100 periods rapidly carrying away the excess units of heat, but only in sufficient degree, all unite in maintaining in an automatic manner substantially a constant degree of 105 temperature within the combustion chamber 110 under varying load conditions upon the engine.

The means whereby intermittent ebullition and consequent rapid removal of a portion of the heated water and steam, followed by an inflow of colder water into the water chamber from the feed cup past the check valve, is produced, is the gist of our invention, and

What we claim and desire to secure by Letters Patent is:

1. In an internal combustion engine including, in combination, a power cylinder and a combustion chamber; a water chamber surrounding said cylinder and said combus-

tion chamber in which a steam pocket is adapted to be formed, a constant level feed cup communicating with said water chamber and with a source of water supply, to 5 keep the proper amount of water in said water chamber, a check valve located in the passage between said cup and water chamber to prevent a backward flow of water, and an eduction outlet properly communicating with said water chamber and leading 10 to a level above said feed cup whereby an intermittent outflow of hot water located between said steam pocket and eduction outlet from said water chamber, followed by an 15 inflow of colder water into said water chamber, results during the operation of the engine.

2. An internal combustion engine including, in combination, a power cylinder and a 20 combustion chamber, a water chamber surrounding said cylinder and combustion chamber in which a steam pocket is adapted to be formed, a constant level water feed cup communicating with said water chamber below its upper level and with a source of water supply to keep the proper amount of water in said water chamber, a check valve 25 located in the passage between said cup and water chamber to prevent a backward flow of water from said water chamber, and an eduction outlet properly communicating with the upper level of said water chamber and leading therefrom to a level above said feed cup whereby an intermittent outflow of 30 hot water located between said steam pocket and eduction outlet from said water chamber, followed by an inflow of colder water into said water chamber, results during the 35 operation of the engine.

40 3. An internal combustion engine including in combination, a power cylinder and a combustion chamber, a water jacket surrounding said cylinder in which a steam pocket is adapted to be formed, a source of 45 water supply, means including a gravity feed device for connecting said water chamber with said source of supply, a check valve forming part of said connection and closing against said water chamber, said gravity 50 feed device having a water level to maintain the proper water level in said water chamber, and an overflow outlet leading from said water chamber to a level above said feed device whereby an intermittent 55 outflow of hot water located between said steam pocket and overflow outlet from said water chamber, followed by a flow of colder water into said chamber, results during the 60 operation of the engine.

65 4. An internal combustion engine including, in combination, a power cylinder and a combustion chamber, a water chamber surrounding said cylinder and combustion chamber in which a steam pocket is adapted to be formed, a source of water supply, a

constant level gravity feed water cup communicating with said water chamber to maintain the proper water level in said water chamber, a check valve located in the passage connecting said cup and water chamber and closing against pressure within said chamber, said cup being connected with said source of water supply, a pump forming part of said connection, and an outflow pipe properly located with respect to and leading 70 from said water chamber to a level above said feed cup to said source of water supply whereby an intermittent outflow of hot water located between said steam pocket and said outflow pipe from said water chamber, 75 followed by an inflow of colder water into said water chamber, results during the 80 operation of the engine.

5. An internal combustion engine including, in combination, a power cylinder and a 85 combustion chamber, a water jacket therefor in which a steam pocket is adapted to be formed, a water tank adjacent to said engine, a pump operatively connected with said engine and having an inlet pipe connection with the lower part of said tank, an outflow pipe leading from said pump to the upper part of said tank, a constant level gravity feed water cup arranged with respect to said water jacket to maintain the 90 proper water level therein, said cup communicating with said water jacket at a point below the normal water level therein, a check valve located in the passage between said cup and water jacket and closing against 95 pressure within said chamber, an inflow pipe between said pump and cup, an outlet pipe leading from said cup to the bottom of said tank, a check valve in said last mentioned outflow pipe closing against said 100 tank, and an eduction pipe properly located with respect to and leading from said water jacket to a level above said cup and to said tank, whereby an intermittent outflow of hot 105 water located between said steam pocket and eduction pipe from said jacket, followed by an inflow of colder water into said water jacket, results during the 110 operation of the engine.

6. An internal combustion engine including, in combination, a power cylinder and a combustion chamber, a water jacket therefor in which a steam pocket is adapted to be formed, a water tank, a pump operatively connected with said engine and having an 115 inflow pipe connection with said tank, a condenser having a pipe connection with the upper part of said tank, an outflow pipe connecting said pump and condenser, a constant level gravity feed water cup adapted 120 to maintain the proper water level within said water jacket and communicating with said water jacket below the water level therein, a check valve located in the passage between said cup and water jacket to pre- 125 130

- 4
- 5 vent a backward flow of water, connections between said pump and cup, an outflow pipe leading from said cup to said tank, a check valve located in said outflow pipe and closing against said tank, and an overflow pipe 55 properly located with respect to and leading from the upper part of said water jacket to a level above said feed cup to said condenser whereby an intermittent outflow 60 of hot water located between said steam pocket and overflow pipe from said jacket, followed by an inflow of colder water into said jacket, results during the operation of the engine.
- 10 15 7. In an internal combustion engine, the combination of a cylinder, a water jacket therefor, means having one level for supplying water to said jacket, overflow means at a higher level than said supplying means, 65 20 means whereby the overflow is rendered intermittent and caused by steam generated in said jacket, and means to prevent a backward flow of said water.
- 25 8. In an internal combustion engine, the combination of a cylinder, a liquid containing jacket therefor, means having one level for supplying a liquid to said jacket, overflow means at a higher level than said supplying means, means whereby the 70 30 overflow is rendered intermittent and caused by said liquid changing to a vaporized state within said jacket, and means to prevent a backward flow of said liquid.
- 35 9. In an internal combustion engine, the combination of a cylinder, a fluid containing jacket therefor, means having one pressure for supplying a fluid to said jacket for cooling purposes, an outlet member for said jacket requiring a higher pressure to expel 40 said fluid, the additional pressure being generated in said jacket, and means to prevent a backward movement of said fluid.
- 45 10. In an internal combustion engine, the combination of a cooling jacket, supplying means therefor, an overflow member discharging at a higher level than said supplying means, and means for causing an intermittent discharge from said jacket through 50 said overflow member.
- 55 11. In an internal combustion engine, the combination of a cylinder, a water jacket therefor in which a steam pocket is adapted to be formed in one portion thereof, means having one level for supplying water to said jacket, overflow means located at another point of said jacket and at a higher level than said supplying means, means whereby the overflow is caused by steam generated in said jacket, the water between said steam pocket and overflow being discharged intermittently, and means to prevent a backward flow of said water. 55 60
12. In an internal combustion engine, the combination of a cylinder, a water jacket therefor containing water and means for intermittently ejecting water therefrom in response to temperature conditions of said cylinder. 65
13. In an internal combustion engine, the combination of a cylinder, a water jacket therefor containing water, and means for intermittently ejecting water therefrom and adding other water thereto in response to temperature conditions of said cylinder. 70
14. In an internal combustion engine, the combination of a cylinder, a water jacket therefor containing water, means for intermittently ejecting water therefrom and permitting the admission of other water thereto in response to temperature conditions of 80 said cylinder, and means to prevent a backward flow of said water. 75
15. In an internal combustion engine, the combination of a cylinder, a water jacket therefor, and a water circulating system including means for producing in a part thereof a continuous flow of water and in another part including said cylinder water jacket an intermittent flow of water. 85
16. In an internal combustion engine, the combination of a cylinder, a water jacket therefor, a water circulating system including means for producing in a part thereof a continuous flow of water and in another part including said cylinder water jacket an intermittent flow of water, and means to prevent a backward flow of water. 90 85
